GOLFER'S TRAINING RACK

Edward W. Botts, Chicago, Ill.

Application June 19, 1940, Serial No. 341,247

2 Claims.

(Cl. 273—35)

The present invention relates to a mechanical body holding or positioning device for enforcing proper golf stance and more particularly to an adjustable, mobile training rack.

It is the usual practice in teaching golf to instruct the golfer in the correct positions of his body during a complete swing of the golf club. Even though the pupil is taught to know every correct position, the execution of hitting a golf ball continually varies. These variations are due mainly to differences in muscular reactions and in the inability to maintain the proper body balance during the club swing.

To obtain and maintain a correct swing requires a shifting of the body while holding the head stationary and the feet on the same ground surface. By helping the body extremities to maintain their relative positions, continual practice permits substantially the same muscular reactions and teaches the correct swing of the trunk and limbs together with the necessary pivoting. In other words, a golfer's swing is "grooved" and if practiced sufficiently the same muscular reactions maintain the golfer's body in the same stance when in actual play as when practicing within the training rack.

Furthermore, instruction by a golf professional is usually expensive and unless the instructor is present continually during practice or the playing of an actual game, the same or new faults in swinging motions with a club reappear.

It is, therefore, an object of this invention to provide a means which self-teaches a golfer to hold and maintain his body in the same correct positions during successive swinging motions in making golf shots.

Another object of this invention is to provide a teaching device for golfers which is adjustable to suit golfers of various heights and reaches.

Another object of the invention is to provide a mechanical device for self-teaching the art of golf which requires but one adjustment by an instructor whereby the pupil can thereafter practice alone.

Still another object of this invention is to provide a teaching device for golf which holds a golfer's head in its proper position during the backswing and the downswing of a club without interfering with the pivotal movements of the body.

Another and still further object of the present invention is to provide a mechanical device for teaching golfers which does not interfere with the golf club during its entire swinging movement.

A further object of the present invention is to provide an adjustable mechanical device for instructing golfers which is mobile, inexpensive in construction, durable and highly efficient.

5 The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawings, in which:

Figure 1 is a side view in elevation of a device embodying the principles of this invention diagrammatically illustrating a golfer with his head being maintained in position when the body has assumed a proper stance;

Figure 2 is a front view of the golfer and the training device shown in Figure 1;

Figure 3 is an enlarged fragmental cross-sectional view, with a part in elevation, of a portion of the device of this invention taken substantially along the plane indicated by the line III—III of Figure 1; and

Figure 4 is a fragmentary cross-sectional view taken along the line IV—IV of Figure 1.

In general, the present invention comprises a tubular structure 10 including a helmet construction 11 for holding a golfer's head 12 in an adjusted position when assuming a proper golf stance and which permits pivotal movements of the body as the golfer swings the club 13.

As shown in Figure 1, the training rack 10 includes a flat base 14 of suitable dimensions and material to provide a sufficient support for the structure carried thereby without being too heavy to permit the unit to be easily moved around a golf training course.

If desired, slats or cleats 15 may be provided on the under side surface of the base 14 to sink into the ground surface thereby eliminating shifting of the base when the device is in operation.

At one end of the base 14 there is provided an upright standard 16 formed preferably from tubular metal stock. A hollow fitting 17 is threaded or otherwise suitably connected to the lower end of the standard 16 and is provided with sufficient transverse openings by means of which the angularly extending legs 18, 19 and 20 are connected thereto.

Each of the legs is formed preferably as a tubular member or a pipe having threaded ends, the upper ends of which are connected to the hollow fitting 17 by means of angular street elbows

21. Similar street elbows 21 connect the lower ends of the legs to floor flanges 22 which are connected to the base 14 by means of bolts, screws or the like (not shown). The legs 18, 19 and 20 provide angular braces for the upstanding standard 16 and their angularity is dependent entirely on the angularity of the street elbows used. As shown, the street elbows 21 are of the 45° type. This angularity may be otherwise if desired and circumstances will permit.

As shown in Figures 1 and 3, a row of tapered apertures 23 are provided for a portion of the length of the standard 16 adjacent its upper end.

A substantially V-shaped supporting member 24 is formed of diverging tubular legs 25 and 26 having their convergent ends threadedly connected to a Y-fitting 27. The inside diameter of the leg 25 is sufficiently large to slidily embrace the standard 16.

On the lower flange of the Y-fitting 27 there is provided a suitably threaded aperture for receiving a set screw 28 (Figure 3) having a hand wheel 29 connected to one end thereof and its inner end 28a shaped to complementally seat within one of the tapered apertures 23. This arrangement permits the V-shaped supporting member 24 to be adjusted lengthwise of the standard 16 and to be held stationary in a desired adjusted position by the seated engagement between the set screws 28 and a registered aperture 23.

At the upper end of the leg 25, there is provided an angle T or stair rail fitting 30. The angularity of this fitting may be varied as desired. As illustrated in Figure 1, the fitting 30 is provided with a transversely extending hollow portion having an axis approximately 30° from the horizontal.

A T fitting 31 is connected to the upper end of the leg 26 with the leg being bent angularly 40 to a position in which its transverse axis is in alignment with the angular axis of the angle T 30.

An arm 32, preferably a metal tubing, extends through the aligned openings of the angle T 30 and the T fitting 31 and is slidily supported thereby. A set screw arrangement having a hand wheel 33 is provided through a side wall of the angle T 30 to be threaded into surface engagement with a sidewall of the arm 32 for holding it in an adjusted position to which it is moved in an endwise direction (Figure 4). If desired, this set screw arrangement may be shaped similarly to the set screw 28 and a row of tapered apertures provided in the arm 32 in the same manner and for the same purpose as provided in the standard 16.

To present a more pleasing appearance, a cap 34 is threaded or otherwise suitably connected to the forward end of the arm 32.

Spaced metal straps 35 and 36 are connected to the arm 32 adjacent its top end. A helmet 37, preferably a football helmet or the like, is connected through its rim 38 to the angularly bent strap portions 39 and 40 by means of rivets 41. The straps 35 and 36 together with the helmet 37 form the helmet construction 11.

It is to be noted that the tubular construction of this device is arranged to be adjusted in a vertical and in a transverse direction.

If desired, the V-shaped supporting member 24 and the arm 32 may be replaced by a single tubular member having an inside diameter equal to that of the leg 25 and shaped to define the same angle as the leg 25 and the portion of the

5 arm 32 extending forwardly of the leg. Such a member would be adjustable vertically in the same way as the leg 25 but provision for lateral adjustment would be lacking. This would be unnecessary if the arm portion extended forwardly a sufficient distance to provide for necessary clearance with golfers having a long reach.

10 A friction mat 42 is connected to the base 14 adjacent the angular braces supporting the standard 16. This mat is formed of yieldable material such as rubber or the like to prevent the golf pupil's feet 43 from sliding when practicing swinging the golf club 13.

15 A T mat 44, of yieldable material such as rubber, is connected to the base 14 at the end opposite the angular braces supporting the standard 16. This mat is sufficiently large and spaced from the mat 42 to permit a golf ball 45 to be teed thereon irrespective of the height or reach of the golfer and the length of the club 13 which he uses.

20 It is only necessary in the device of this invention that a golf instructor place the pupil in a position in which his body, including his feet and head, assume a proper stance when addressing a golf ball. With the pupil's body in the proper position, the instructor adjusts the tubular construction so that the helmet 37 embraces the pupil's head 12. This restricts movement of the pupil's head in upward and lateral directions.

25 With the pupil's head and feet maintained in the proper balanced stance, other portions of his body including the trunk and legs are free for pivotal movements which take place during the back swing and downward swing of the golf club.

30 It is to be noted in Figure 1 that the angular arrangement of the arm 32 is to permit a full swing of the club 13 without interfering with the tubular structure of the rack device.

35 From the foregoing description it will be apparent that the invention provides an adjustable training device for golfers which holds the head and feet in a proper adjusted stance while at the same time permitting the other body portions of the golf pupil to pivot freely as the golf club is swung.

40 While a particular embodiment only of this invention has been illustrated, it will, of course, be understood that the invention should not be limited thereto, since many modifications may be made and, therefore, it is contemplated by the appended claims to cover all such modifications as fall within the true spirit and scope of the present invention.

45 I claim as my invention:

1. A mobile device for use in teaching the art of golf comprising a tubular standard having a row of apertures intermediate its ends, angularly extending foot braces on said standard for holding it in an upright position, a V-shaped member having tubular legs, one of said legs being arranged to embrace said standard for sliding movement therealong, screw means on said V-shaped member having an end arranged to seat in one of said row of apertures for holding said member in an adjusted position to which it is moved, spaced tubular members carried at the divergent ends of said legs and being arranged in axial alignment, a longitudinally movable tubular arm extending through said spaced tubular members, means for holding said arm in an adjusted position to which it is moved, and means on said arm for holding a golfer's head in its adjusted position when the golfer assumes a proper stance.

2. A device for use in teaching the art of golf comprising a flat base, cleats on said base for gripping the surface supporting said base, a tubular standard at one end of said base and having a row of sidewall apertures intermediate its ends, 5 angularly extending foot braces connecting said standard to and in spaced relation from said base, a V-shaped member having divergently extending tubular legs, one of said legs being arranged to embrace said standard for sliding movement therealong, set screw means carried by said V-shaped member at its ends defined by the converged legs and being arranged to seat in one of said row of apertures for holding said member in 10

an adjusted position to which it is moved, spaced tubular members carried at the divergent ends of said legs and being arranged in axial alignment, a longitudinally movable tubular arm extending through said spaced tubular members in angular relation to the longitudinal axis of said standard, means for holding said arm in an adjusted position to which it is moved, and head holding means on said arm adjacent an end thereof whereby a golfer upon assuming a proper stance on said base will have his head held stationary while the rest of his body is free to pivot during a golf swing.

EDWARD W. BOTTTS.
